DESIGN FOR AN ELECTRIC IRON OR SIMILAR ARTICLE

Joseph E. Barrett, Cape Girardeau, Mo., assignor
to Superior Electric Products Corp., St. Louis,
Mo., a corporation of Missouri

Application August 11, 1938, Serial No. 79,238

Term of patent 3½ years

To all whom it may concern:

Be it known that I, Joseph E. Barrett, a citizen of the United States, residing in the city of Cape Girardeau, county of Cape Girardeau and State of Missouri, have invented a new, original, and ornamental Design for an Electric Iron or Similar Article, of which the following is a specification, reference being had to the accompanying drawing, forming a part thereof.

In the drawing: Fig. 1 is a top or plan view of

an electric iron or similar article, showing my new design; Fig. 2 is an elevation of the left side of the electric iron shown in Fig. 1, and Fig. 3 is an elevation of the right side of the electric iron in Figs. 1 and 2.

I claim:

The ornamental design for an electric iron or similar article, substantially as shown.

JOSEPH E. BARRETT.
